FIG. 1.

FIG. 2

Fig. 1 is a fragmentary view of a section of the interior of an airplane; and

Fig. 2 is a perspective view of an airplane embodying our new design.

The dominant features of the design reside in the portions shown in full lines, the design being especially characterized by the features of the interior shown in full lines in Fig. 1.

We claim:

The ornamental design for an airplane, as shown and described.
